SAFETY INTERLOCK FOR MACHINE GUN BARREL

Patrick E. Sweeney, Baltimore County, Md., assignor to Aircraft Armaments, Inc., Cockeysville, Md., a corporation of Maryland

Filed Jan. 7, 1960, Ser. No. 1,066

5 Claims. (Cl. 89—14)

This invention relates in general to automatic machine guns, and more particularly to a safety interlock for permitting the barrel of a machine gun to be quickly changed.

In guns of the class described, the barrel assembly, which may include the barrel and an extension to the barrel upon which the bolt assembly is mounted, is slideably mounted in the gun receiver for reciprocation between battery and recoil positions. It is conventional to attach the barrel to the barrel extension such that the barrel can be removed for replacement after a certain period of use. One of the problems associated with quickly changing the barrel is that of insuring proper head space or distance between the shoulder in the cartridge chamber of the barrel and the bolt block face when the latter is in firing position. Generally, the barrel is threaded into the barrel extension requiring gaging of the axial position of the barrel in order to insure proper head space before the barrel is locked in position. A failure to provide adequate head space can result in jamming of the gun, while head space in excess of that which is proper can result in rupture of a cartridge on firing. Thus, when a barrel is changed, it is essential that time be taken to gage the new barrel to insure the proper amount of head space.

It is therefore an object of this invention to provide a connection between barrel and barrel extension which requires merely the axial insertion and rotation of the barrel in the barrel extension to insure proper locking of the barrel to the extension and creation of the proper head space.

As a feature of this invention whereby the object thereof is achieved, interengaging lugs on the barrel and barrel extension permit insertion of the barrel into the barrel extension to a fixed depth and rotation of the barrel until a spring-loaded detent snaps into place and holds the barrel at a particular angular position at which the lugs on the barrel and barrel extension cooperate to prevent withdrawal of the barrel. The head space is automatically fixed and all that is necessary to be done is to insert and rotate the barrel through a sufficient angle after insertion. Because of the simplicity of the above described connection, it is desirable to prevent firing of the gun if, in haste to change barrels, the new barrel is not rotated sufficiently for the detent to be effective. This result is accomplished by providing a safety lever on the barrel extension which normally is positioned in the path of the bolt assembly carrying the firing pin and prevents the firing pin from contacting and firing a cartridge in the chamber of the barrel. The barrel is provided with a cam which is engageable with the lever upon rotation of the barrel such that its rotation to the angular position where the detent is effective cams the safety lever out of the path of the bolt assembly. In this manner, a cartridge in the chamber can be fired only after the barrel is properly attached to the barrel extension.

The more important features of this invention have thus been outlined rather broadly in order that the de-

tailed description thereof that follows may be better understood, and in order that the contribution to the art may be better appreciated. There are, of course, additional features of the invention that will be described hereinafter and which will also form the subject of the claims appended hereto. Those skilled in the art will appreciate that the conception upon which this disclosure is based may readily be utilized as a basis for designing other structures for carrying out the several purposes of this invention. It is important, therefore, that the claims to be granted herein shall be of sufficient breadth to prevent the appropriation of this invention by those skilled in the art.

In the drawings:

15 Figure 1 is a top sectional view taken along the line 1—1 of Figure 2 and showing a machine gun with the barrel properly locked into the barrel extension and the bolt assembly in position for firing a cartridge in the chamber of the barrel.

20 Figure 2 is a side sectional view of the machine gun shown in Figure 1.

Figure 3 is a top sectional view similar to Figure 1 but showing the barrel improperly attached to the barrel extension and the bolt assembly held back from its firing position.

25 Figure 4 is a side sectional view of the machine gun shown in Figure 3.

Figure 5 is a sectional view taken along the line 5—5 of Figure 1 and showing the safety lever in an inoperative position.

30 Figure 6 is a sectional view taken along the line 6—6 of Figure 3 and is similar to Figure 5 except that parts are broken away to show the safety lever in operative position.

35 Figure 7 is a perspective view of the forward end of the barrel extension showing the locking lugs thereon.

Figure 8 is a perspective view of the rear end of the barrel showing the locking lugs thereon and the cam surface for moving the safety lever.

40 Referring now to Figure 1, reference numeral 10 designates an automatic machine gun having a receiver 11 with a forward portion 12, a rearward portion 13, and intermediate portion 14. Portion 13 is formed with longitudinally extending guide rails 15, and portion 12 is formed with bearing surface 16 and apertures 17. Portion 14 is provided with grooves 18 for the reception of accelerator housing 19 upon which accelerator 20 is pivotably mounted at 21. Accelerator 20 is biased by springs (not shown) toward wall 22 on receiver 11.

45 50 Slideably mounted within portion 13 of receiver 11 is barrel extension 23 which has bearing grooves 24 on each side (see Figure 7) engaged with rails 15. Barrel extension 23 has a forward portion 25 (i.e., the portion to which the barrel is attached) which extends across the width of portion 13 of receiver 11, and rearwardly directed legs 26 on each side. Legs 26 have grooves 24 on their outer faces. The inner faces of legs 26 contain bolt assembly grooves 27 which extend the entire length of the barrel extension.

55 60 Bolt assembly 30 has two main parts: bolt slide 31, and bolt block 32. Bolt slide 31 has flanges 33 slideably engaged in grooves 27. Beneath flanges 33 is tubular portion 34 having aperture 35 in cylindrical spring well 36 through which bolt return spring rod 37 passes.

65 65 Bolt return spring 38 has one end engaged against the rear of receiver 11 (not shown) and one end engaged in well 36 for constantly urging bolt assembly 30 forwardly toward wall 22 of receiver 11. Above flange 33 is firing pin holder 39 which is provided with a longitudinal slot 40 in which slide 41 of bolt block 32 is engageable. Slide 41 is provided with elongated hole 42 through which passes pin 43 attached to holder 39. In

this manner, bolt block 32 is connected to bolt slide 31 for limited relative movement. Rigidly attached to holder 39 is firing pin 44 which extends through aperture 45 in bolt block 32 and can project therefrom as seen in Figure 1. Pivotal mounted on each side of bolt block 32 are locking latches 46 which are engageable in keeper notches 47 formed in the inner face of legs 26 of barrel extension 23 when the bolt block is at its forward most position on the barrel extension.

Bolt block 32 has extractor cam 48 pivotally mounted below aperture 45 and biased upwardly toward the aperture. Cam 48 is engageable with the rim of a cartridge for extracting the same from the chamber of the barrel when the bolt block is moved rearwardly by bolt slide 31. Cam 48 has ears (not shown) which are engageable with extractor grooves 49 on the inner faces of legs 26 to control movement of the cam relative to the rest of the bolt block when the bolt block moves relative to the barrel extension. Above aperture 45 is stripper cam 50 which engages the base of a fresh cartridge above and behind portion 25 of the barrel extension during forward movement of bolt assembly 30 under the effect of return spring 38.

Pivoted mounted on receiver 11 is detent lever 51 having arm 52 extending through slot 53 in receiver 11. Lever 51 has aperture 54 in which pin 56 can slide transversely, rotation of pin 56 being prevented. Pin 56 has a portion which is circular (Figure 4) and a portion which has ears thereon (Figure 2). When pin 56 is in the position shown in Figure 1, lever 51 is locked against rotation because the ears on the pin engage corresponding notches in receiver 11. When pin 56 is transversely moved relative to lever 51, the ears on pin 56 are withdrawn from a portion of aperture 54 and lever 51 can then be manually rotated against spring pressure to draw arm 52 upwardly. Pin 56 may be biased toward its position where the ears lock lever 51 against rotation.

Barrel 60 has axially extending bore 61 therein which connects at one end with chamber 62. Shoulder 63 in the chamber limits forward movement of a cartridge in the chamber and positions the cartridge properly for firing. The chambered end of barrel 60 has a portion 64 of reduced diameter that is connected to an intermediate portion 65 at shoulder 66. Forward of intermediate portion 65 is bearing ring 67 of the same diameter as bearing 16 in receiver 11. Bearing ring 67 has axial recesses 68 which serve to lighten the barrel and prevent distortion of the barrel due to the heat generated when the gun is continuously fired. Axial slot 69 is formed in the surface of portion 65. Bolt locking lugs 70 and 71 are formed on the free end 72 of the barrel adjacent chamber 62. Lugs 70 and 71 are located 90° on each side of the location of slot 69 and are thus 180° apart as shown best in Figure 8. Lug 70 has radial end faces 72 and lug 71 has radial end faces 73 to define lugs which extend circumferentially through approximately one quadrant on opposite sides of portion 64. The one face 73 facing in the direction of groove 69 has semicircular recess 74 therein. Projecting beyond the plane of the rear face 75 of the barrel and adjacent an end face 72 of lug 70 is cam 76 which has a portion forming a continuation of the cylindrical surface of portion 64. Cam 76 includes lever engaging face 77 whose function will be explained hereinafter.

Portion 25 of barrel extension 23 has a rectangular recess 80 into which bolt assembly 30 can enter. Barrel aperture 81 connects forward face 82 of barrel extension 23 with recess 80. Recess 81 is of a diameter sufficiently large to permit rotation therein of free end 72 of the barrel. Extending radially into recess 81 are barrel extension locking lugs 83 and 84, which form continuations of face 82. Lugs 83 and 84 are oppositely spaced 180° apart and are about one quadrant in length. The clearance between the crests of lugs 83 and 84 is substantially equal to the diameter of portion 64 on the barrel.

Mounted to one side of the center line of barrel ex-

tension 23 is stop pin 85 which projects radially into aperture 81. Pin 85 is located axially inwardly of face 82 a sufficient distance so that it engages recess 74 in lug 71 on the barrel. Barrel extension 23 has a vertical hole 86 which extends from the top of the barrel extension downwardly into recess 80 and aperture 81. The forwardmost edge of hole 86 is rearward of pin 85 such that it is substantially aligned with face 75 of the barrel when shoulder 66 of the barrel abuts face 82 of the barrel extension (see Figures 2 and 4). Safety lever 87 is pivotally mounted in hole 86 on pin 88 that is connected to the barrel extension. Torsion spring 89 coiled around pin 88 has one end attached to the lever and the other end (not shown) bearing on an edge of hole 86. Spring 89 is mounted so that lever 87 is continuously urged to a position shown in Figure 6 where end portion 90 projects into the path of bolt block 32. The projection of the bolt block is shown by the phantom lines in Figures 5 and 6. Hole 86 is large enough so that lever 87 can pivot against the action of spring 89 out of the path of bolt block 32 as shown in Figure 5.

The attachment of barrel 60 to barrel extension 23 will now be described. Barrel 60 is slidably and rotatably mountable in receiver 11 because of bearing ring 67 and bearing 16. Barrel 60 has another bearing forward of ring 67 that also engages a bearing on the forward end of the receiver, but these bearings are not shown. Pin 56 is moved in aperture 54 in lever 51 such that the latter may manually be moved against spring pressure to the position shown in Figure 4. While the lever is depressed, barrel 60 is inserted into barrel extension 23 by being moved axially (to the left as viewed in Figure 4) with lugs 70 and 71 positioned 90° out of alignment with lugs 83 and 84. In this manner, the free end portion 64 of the barrel can be inserted into aperture 81 until shoulder 66 on the barrel abuts face 82 on the barrel extension, and lever 51 is held in the position shown in Figure 4 by portion 65 of the barrel. Because the lugs on the barrel are now interior to the lugs on the barrel extension (see Figure 3), the barrel can now be rotated 90° until groove 69 opens upwardly. The position of the barrel is as shown in Figures 1 and 2 and lever 51 snaps into groove 69. In addition, stop pin 85 enters notch 74 in lug 71 and prevents further rotation of the barrel beyond the point where the lugs on the barrel are directly behind the lugs on the barrel extension. In this position, barrel 60 cannot be withdrawn from the barrel extension. As best seen in Figures 5 and 6, the above described insertion and rotation causes cam 76 to move safety lever 87 such that portion 90 is out of the path of bolt block 32. With the barrel attached as described above, the distance between shoulder 63 in the chamber (Figure 2) and the forward face of bolt block 32, when the latter is positioned with latches 46 engaged in keepers 47, defines the head space. Thus, by simply inserting and rotating the barrel, the proper head space is achieved.

Assume now that the barrel is properly attached to the barrel extension and that the bolt assembly 30 is rearward of the position shown in Figure 1. Stripper came 50 on bolt slide 31 engages the base of a cartridge as the bolt slide is driven forward by return spring 38. The cartridge is cammed downwardly by a chambering ramp on receiver 11 until extractor cam 48 is engaged in the extractor groove in the cartridge and the bolt block engages the base of the cartridge. Further forward movement of the bolt assembly causes the cartridge to be inserted into chamber 62 by the action of bolt block 32. During this forward movement, the bolt slide and bolt block are positioned relative to each other as shown best in Figure 3. If safety lever 87 is in its inoperative position, bolt block 32 drives the cartridge into the chamber until it seats against shoulder 63. Forward movement of block 32 ceases as bolt slide 31 continues forward movement simultaneously camming latches 46 into keepers 47 and causing firing pin 44 to move through

the bolt block to strike and fire the cartridge. The bolt assembly is now locked to the barrel assembly and both recoil together. Recoil of the barrel causes ring 67 to impart pivotal movement to accelerator 20 against its spring. However, the curvature of the accelerator is chosen so that during initial recoil, the portion of the accelerator contacting well 36 on the bolt slide moves axially through the same displacement as the barrel. This prevents any relative movement between the bolt assembly and the barrel extension during initial recoil and permits reduction in the gas pressure in the barrel before the cartridge is extracted. As the barrel recoils further, accelerator 20 causes relative movement between bolt slide 31 and the barrel extension storing energy in spring 38. Simultaneously, firing pin holder 39 is withdrawn from its camming position between latches 46 as pin 43 moves in slot 42 in bolt block 32. Further movement of bolt slide 31 relative to the barrel extension first causes keepers 47 to cam latches 46 inwardly toward the firing pin and then causes rearward movement of the bolt block with the bolt slide thus extracting the spent cartridge from the chamber as the barrel is buffered and return to battery position by buffer springs (not shown) acting on the legs of the barrel extension. The inner surfaces of legs 26 engage latches 46 to prevent relative movement between the bolt slide and bolt block at all times except when the latches are aligned with the keepers.

The spent cartridge is removed by apparatus not shown and the bolt assembly repeats the cycle being driven forward by spring 38. However, now assume that the barrel is improperly attached to the barrel extension and that portion 90 of lever 87 projects into the path of bolt block 32. Spring 38 drives the bolt assembly forwardly causing a fresh cartridge to enter chamber 62. Forward movement ceases when the bolt block strikes the safety lever. However, bolt slide 31 cannot move relative to the bolt block as shown in Figures 3 and 4 because latches 46 are not aligned with keepers 47. As a result, firing pin 44 cannot strike and fire the cartridge, and the gun cannot function.

It can now be appreciated that with this invention an extremely simple connection between a barrel and barrel extension is achieved while at the same time insuring against accidental firing if the barrel is improperly connected.

What is claimed is:

1. In a machine gun having a gun barrel connected to one end of a barrel extension slideably mounted in a receiver so that the chamber of the barrel is adjacent said one end, a bolt assembly mounted on said barrel extension for reciprocatory movement thereon from one terminal position adjacent said one end of the barrel extension to another terminal position remote from said one end, said bolt assembly having a firing pin thereon for contacting and firing a cartridge in the chamber when the bolt assembly moves to said one terminal position; a safety interlock for attaching the barrel to the barrel extension comprising: means to effect insertion of said barrel into said barrel extension only at a given angular position of the barrel relative to the barrel extension, means to effect rotation of said barrel after insertion and prevent its withdrawal from the barrel extension, stop means to limit rotation of the barrel so that after its insertion and rotation the barrel has another angular position different from said given angular position, movable means on said barrel extension positioned in the path of said bolt assembly for preventing movement of the latter to said one terminal position, and means on said barrel for camming said movable means out of the path of said bolt assembly upon rotation of said barrel to the limit determined by said stop means.

2. In the machine gun of claim 1, selectively oper-

able means for preventing rotation of said barrel away from said other angular position.

3. The combination with a gun barrel having a chamber at one end, a barrel extension having an aperture therein for receiving said one end of the barrel, and a bolt assembly slideably mounted on said barrel extension for firing a cartridge in the barrel chamber when the bolt assembly moves to a certain location on the barrel extension; of a safety interlock for attaching the barrel to the barrel extension comprising a movable safety lever mounted of said barrel extension, said safety lever having an operative position in the path of said bolt assembly movement of the same to said certain location and preventing the firing of a cartridge in the barrel chamber, said safety lever having an inoperative position out of the path of said bolt assembly for effecting movement of said bolt assembly to said certain location and the firing of a cartridge in the barrel chamber, means constantly urging said safety lever to said operative position, locking lugs projecting from said one end of said barrel, latching lugs on said barrel extension projecting into the aperture, said lugs being cooperable for preventing insertion of said one end of said barrel into said aperture at all but one angular position of the barrel, said lugs being cooperable for preventing withdrawal of the barrel from the aperture after the barrel is rotated away from its one angular position, stop means to engage said barrel after rotation away from its one angular position for limiting such rotation, selectively operable means for preventing rotation of said barrel toward said one angular position after said barrel engages said stop means, and cam means on said one end of said barrel, said cam means being engageable with said safety lever only when said barrel is rotated toward said stop means, rotation of said barrel against said stop means causing said cam means to move said safety lever from operative to inoperative position.

4. In combination: a generally cylindrical gun barrel having an axial chamber at one end, said chamber adapted to receive a cartridge, said one end having radial extending lug means; a barrel extension having an axial aperture at one end sufficiently large to receive said lug means, said barrel extension having lug means extending radially into the aperture, the lug means on said barrel extension and barrel being cooperable to effect axial insertion of said end into said aperture when said barrel has a first angular position relative to the barrel extension, said lug means being cooperable after said end is inserted in said barrel to effect rotation of said barrel away from said first angular position and to prevent its axial withdrawal, stop means on said barrel extension to limit rotation of the barrel to a second angular position, a bolt assembly slideably mounted on said barrel extension for movement to an operative position adjacent said one end thereon, said bolt assembly having a firing pin thereon for contacting and firing a cartridge in the chamber when said bolt assembly is in its operative position, a safety lever mounted on said barrel extension for movement from an operative position to an inoperative position, the operative position of said lever being in the path of the bolt assembly for preventing movement of said bolt assembly to its operative position, the inoperative position of said lever being out of the path of the bolt assembly for effecting movement of said bolt assembly to its operative position, spring means constantly urging said lever to its operative position, and cam means being engageable with said lever upon rotation of said barrel toward said second angular position for moving said lever against the action of said spring means, movement of said barrel to said second angular position causing movement of said lever to inoperative position.

5. In a machine gun having a receiver, a member slideably mounted in said receiver, a bolt assembly slideably mounted on said member for reciprocatory movement to-

ward and away from a terminal position, a firing pin on said bolt assembly, said firing pin being effective when the bolt assembly is at its terminal position, and a barrel having a chamber in one end for receiving a cartridge, said barrel being slideably and rotatably mounted in said receiver; means for connecting the barrel to the barrel extension comprising: interengaging lug means on said barrel and barrel extension for effecting insertion of the barrel into the barrel extension to a fixed depth and rotation of the barrel thereafter to an angular position preventing withdrawal of the barrel, detent means for retaining said barrel at said angular position, safety lever means mounted on said barrel extension for movement from an operative position to an inoperative position, the

operative position of the lever preventing the bolt assembly from moving to its terminal position and the firing pin from being effective to fire a cartridge in the chamber, the inoperative position of the lever effecting movement of the bolt assembly to its terminal position and firing of a cartridge in the chamber by the firing pin, means constantly urging said lever to operative position, and cam means on said barrel engageable with said lever upon rotation of the barrel, said cam means being effective to move said lever to inoperative position only after said detent means is effective to retain said barrel at said angular position.
